UNITED STATES PATENT OFFICE.

HENRY BRISTOW, OF BROOKLYN, NEW YORK.

DESIGN FOR A BOOK.

SPECIFICATION forming part of Design No. 25,981, dated September 1, 1896.

Application filed July 11, 1896. Serial No. 598,902. Term of patent 7 years.

To all whom it may concern:

Be it known that I, HENRY BRISTOW, a citizen of the United States, residing at Brooklyn, in the county of Kings and State of New York, have invented and produced a new and original Design for Books, of which the following, with the accompanying drawings, is a specification.

Referring to the drawings, Figure 1 is a perspective view showing the book in the closed condition, and Fig. 2 is a similar view showing the book open.

Similar letters of reference indicate the same parts in both figures.

The leading features of my design are the rectangular outline, the covers projecting on three sides and presenting the appearance of woven fabric, the leaves having triangular members on the outer long edges folded inward to conform to the rectangular outline, and the ornamental bow or knot of ribbons placed on the outer edges of the covers at their mid-length.

A A are the covers, the outside surfaces showing as woven fabric.

B B are the leaves, rectangular in general outline, but having the triangular members B B, extending the full length of the outer edge, each having the salient angle b rounded, as shown, and folded inward upon the body 30 of the leaf.

D is the ornamental bow or knot of ribbons arranged at the middle of the outer long edges of the covers.

The whole presents a pleasing and attractive appearance, especially when the colors of the covers, leaves, and ribbons have been selected and combined with due regard to harmony.

I claim—

The design for a book as herein shown and described.

In testimony that I claim the invention above set forth I affix my signature in presence of two witnesses.

HENRY BRISTOW.

Witnesses:

JOSEPH H. MCGOWAN,
JAMES P. JUDGE.
